UNITED STATES PATENT OFFICE.

MICHEAL McNALLEY, OF ST. LOUIS, MISSOURI.

VEHICLE-FASTENING FOR HARNESS.

SPECIFICATION forming part of Letters Patent No. 703,808, dated July 1, 1902.

Application filed March 5, 1902. Serial No. 96,788. (No model.)

To all whom it may concern:

Be it known that I, MICHEAL McNALLEY, a citizen of the United States, residing at St. Louis, in the State of Missouri, have invented 5 certain new and useful Improvements in Vehicle-Fastenings for Harness, of which the following is a full, clear, and exact description.

My invention relates to a vehicle-fastening for harness—that is to say, a fastening which 10 may be made in a variety of analogous forms and used in various relations about a vehicle—such, for instance, as on singletrees, shafts, and neck-yokes.

Reference is to be had to the accompanying 15 drawings, forming a part of this specification, in which similar characters of reference indicate corresponding parts in all the figures.

Figure 1 is a plan view of my invention. Fig. 2 is a central section through the same 20 on the line 2 2 in Fig. 1, and Fig. 3 is a side elevation showing the device as viewed from the left of Fig. 1.

A pointed wooden member 1 is provided with a longitudinal head 2 of substantially 25 conical shape and slightly flattened. Upon this head are integrally mounted bosses 3 4, adjacent to one edge of said head. Mounted upon the opposite edge thereof is an ancillary member 5, provided with bosses 6 7, the three 30 last-mentioned parts constituting a T-shaped member. Upon the upper and lower sides of the head are beads 8 9 and also grooves 10 11, parallel with and adjacent to the respective beads. A pin 12 secures the head 2 in position 35 on the member 1.

My invention is used as follows: A strap A, provided with a slot B, is fitted upon the head in the following manner: The T-shaped member is first inserted through the slot and 40 the strap is bent around into the position indicated in Fig. 1, the raised beads 8 9 serving to hold said strap in the grooves 10 11.

The device may be used for holding traces upon singletrees and for holding straps of 45 any kind upon neck-yokes and shafts. Its

utility will readily suggest itself to persons skilled in the art to which it relates.

Having thus described my invention, I claim as new and desire to secure by Letters Patent—

1. A vehicle-fastening for harness, comprising a longitudinal head of substantially conical shape, said head being provided with oppositely-disposed grooves, cylindrical bosses mounted upon said head adjacent to said grooves, and an ancillary member mounted upon said head and projecting therefrom in a plane substantially at right angles to the general axial direction of said bosses. 55

2. A vehicle-fastening for harness, comprising a longitudinal head of substantially conical shape, said head being provided with oppositely-disposed grooves, cylindrical bosses mounted upon said head adjacent to said grooves, and an ancillary member mounted 60 upon said head and projecting laterally therefrom in a plane substantially at right angles to the general direction of said bosses, said ancillary member being provided with cylindrical bosses parallel with the bosses upon 65 said longitudinal head. 70

3. A vehicle-fastening for harness, comprising a longitudinal head of substantially conical form, a pair of grooves disposed upon opposite sides of said head, beads disposed adjacent to said grooves, a pair of cylindrical bosses disposed upon opposite sides of said head and immediately adjacent to said grooves, a T-shaped member projecting laterally from one of the edges of said head and 75 provided with bosses, said bosses being substantially in alignment with said beads for the purpose of bending the end of a strap. 80

In testimony whereof I have signed my name to this specification in the presence of 85 two subscribing witnesses.

MICHEAL McNALLEY.
